UNITED STATES PATENT OFFICE.

GEORGE W. MCGILL, OF NEW YORK, N. Y.

RING-SUSPENDING DEVICE FOR PAPERS.

SPECIFICATION forming part of Letters Patent No. 299,155, dated May 27, 1884.

Application filed April 4, 1884. (No model.)

To all whom it may concern:

Be it known that I, GEORGE W. MCGILL, a citizen of the United States, residing at the city of New York, in the county of New York and State of New York, have invented certain new and useful Improvements in Ring-Staples for Suspending Papers, Cards, &c.; and I do hereby declare the following to be a full, clear, and exact description of the invention, such as will enable others skilled in the art to which it appertains to make and use the same.

This invention relates to a new and useful improvement in ring-staples for fastening together and suspending several sheets of paper or similar fabrics, and for suspending single-sheet cards, and is designed as an improvement on the suspending staple-ring patented to me by United States Letters Patent No. 253,876, of February 21, 1882.

The invention consists in making the staple and its suspending-ring of two pieces of flexible wire, and bending and connecting them together, as shown in the drawings, in which—

25 Figure 1 represents a perspective view of a suspending-staple made in pursuance of my invention. Fig. 2 represents a card with my suspending-staple attached. Fig. 3 shows the reverse side of Fig. 2. Fig. 4 represents 30 a vertical section of Fig. 2, taken on the line $z z$ of that figure; and Fig. 5 represents a similar vertical view showing the suspending-ring turned down on the front of the card. Figs. 6 and 7 represent modifications in the 35 construction of the device.

To form my ring-staple one piece of suitable wire of proper length is bent so as to form a loop, a , in its central portion. The two ends are then bent apart at an angle to 40 said loop to form the head $b b$, and then bent again at right angles to form the legs $c c$ of the staple. Another piece of wire of proper length is bent to form the hinging suspending ring or loop D , which is hinged to the 45 staple by folding its ends around the top of the staple-loop a , as at $d d$. The suspending ring or loop D being hinged to the staple enables it to be folded down on the surface of the article to which it is attached, as shown 50 in Fig. 5, to admit of the convenient packing or mailing of the same.

This device is peculiarly adapted for use in my machine for inserting and clinching staples patented to me by United States Letters

Patent No. 213,316, of February 18, 1879. 55 When intended for use in my said patented machine, the legs of the staple should slightly diverge from each other, so that said legs will have a slight elastic pressure, when inserted in the machine, against the outer sides or bottom of the guiding grooves, to prevent the staples from falling out before the lever is turned down upon the article to be stapled. After the legs of the staple have been driven through the papers, card, or other fabric, 60 they are bent inward toward each other and clinched down. By means of my said machine the legs are driven through and clinched down by a single blow upon the head of the plunger. When used to bind a number of 65 sheets of paper or other fabrics together, my staple serves both as a fastener and suspending device. The staple is given the head-loop a , and the suspending-ring D is hinged to it at that point to better adapt the device to be 70 operated in my patented staple inserting and clinching machine, hereinbefore referred to. When the wire forming the suspending-ring D possesses some elasticity or spring, its hinging-eyes $d d$ will impinge with a slight elastic pressure on the sides of the staple-loop a and hold the ring up when placed in the position shown in Fig. 2, or down when placed in the position shown in Fig. 5.

In the modified construction of my device 75 shown in Fig. 6 the staple is made without the head-loop a , and the suspending-loop or ring D is hinged to the staple-head direct; and in the modified form of the device shown 80 in Fig. 7 the wire forming the staple is passed through a solid wire ring and twisted so as to 85 form the hinging-eye d' and neck a' , and is then bent apart at right angles thereto to form the head $b b$, and then bent again at right angles to form the staple-legs $c c$.

90 What I claim as my invention, and desire to secure by Letters Patent, is—

As an improved article of manufacture, the 95 adjustable ring-staple for holding and suspending papers, &c., consisting of a staple and a loop or ring, each made of a single piece of wire and hinged together, substantially as shown, to enable the loop or ring to be opened or closed, substantially as set forth and shown.

GEORGE W. MCGILL.
